CLAIM

The ornamental design for a telescopic goal post, as shown and described.

DESCRIPTION

FIG. 1 is a front, top perspective view of a telescopic goal post, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view thereof, shown in an alternative position; and,

FIG. 10 is another rear, bottom view thereof, shown in an alternative position.

The broken lines in the figures illustrate portions of the telescopic goal post that form no part of the claimed design.
